UNITED STATES PATENT OFFICE.

ALBERT G. SCHERER, OF CHICAGO, ILLINOIS, ASSIGNOR TO THE EXCELSIOR STEEL FURNACE COMPANY, OF CHICAGO, ILLINOIS, A CORPORATION OF ILLINOIS.

HOT-AIR DISTRIBUTER FOR FURNACES.

1,224,219.

Specification of Letters Patent.

Patented May 1, 1917.

Application filed November 15, 1913. Serial No. 801,120.

To all whom it may concern:

Be it known that I, ALBERT G. SCHERER, a citizen of the United States, and a resident of Chicago, in the county of Cook and 5 State of Illinois, have invented a certain new and useful Hot-Air Distributer for Furnaces, of which the following is a specification.

It is generally known that with that variety of furnaces in which the heated air is conducted from the furnace to the portion of the premises where it is desired by leads of hot air conduit, it often happens that certain of the leads take a great deal larger 10 proportion of the hot air than is necessary or desirable, while other leads do not get a sufficient quantity. This is occasioned by the fact that some of the leads are larger than others, some are more direct, some are 15 shorter, and some both more direct and shorter. The structural features and conditions of the premises to be heated have to be accepted as they are found, and while the employment of various sized leads will afford sufficient conduit space to get the necessary amount of hot air to the particular 20 size room to properly heat it, the proportion of air which a particular lead will take depends upon so many other conditions than 25 size or capacity, that it is found when the plant is installed that some of the leads are not delivering the amount of hot air which it is desirable they should deliver.

My present invention has for its object 30 the provision of facilities which will permit of an adjustment so as to effect the desired distribution of the hot air from the furnace to the various leads of conduit with which it connects.

40 I attain the above object by the structure illustrated in the accompanying drawing, in which:—

Figure 1 is an elevation of a usual form of hot air furnace a portion of the top of 45 the casing being broken away to show one of my distributing partitions in place;

Fig. 2 is a view looking upward into the top of a furnace casing with my distributor installed therein;

50 Fig. 3 is a view of one of the distributing partitions;

Fig. 4 is a fragmental detail plan of the

central connection for the distributing partitions;

Fig. 5 is a fragmental detail elevation of 55 the structure shown in Fig. 4; and

Fig. 6 is a fragmental detail similar to 60 Fig. 4, showing how more than one distributing plate may be assembled with a single bar 14.

Similar reference characters refer to similar parts throughout the several views.

While my invention may be advantageously employed in any form of plant for the distribution of hot air, I have illustrated the same in connection with the usual form of hot air furnace, which, so far as I know, is by far the most widely distributed and best known apparatus of that kind.

The usual form of hot air furnace comprises a heater and radiator portion surrounded by a casing, 1, as shown in Fig. 1. Air is admitted to the casing, and, after being heated by the heater and radiator, rises to the top or head, 2, of the casing 75 from which it flows through the lead openings, 3, to the leads and through the premises.

I have shown a form of casing top or head, 2, which will facilitate the flow of the heated 80 air. In this form of casing top or head the lower edge, 4, is cylindrical in form and of such size to fit the upper end of the body, 5, of the casing. Above the edge, 4, the casing top or head is given an upwardly and inwardly inclined direction or conical form, 6, in which portion the lead openings, 3, are provided. This arrangement gives the leads an upward direction as they leave the furnace thereby facilitating the easy flow of the 85 light hot air from the furnace to the leads.

Above the lead openings, 3, the walls of the casing top or head incline downwardly and inwardly to a central point 8, in the form of an inverted cone, 9. This form also facilitates the flow of the hot air to the leads as it does away with the central dead space in which the movement of the hot air contiguous thereto would be given no direction and would be permitted to eddy and interfere with the flow of the rest of the hot air.

Secured to and depending from the central point, 8, of the casing head or top, by means of the bolt, 10, is the reel or pintle,

11, comprising the central hub, 12, the end plates, 13, and the bars, 14, which extend between the projections 15, provided upon the peripheries of the plates, 13.

5 Distributing plates, 16, are next provided, of a form to stand and divide vertically a radius of the casing top or head. The inner vertical edge of the distributing plates is provided with a hook, 17, for engaging one 10 of the bars, 14, and the outer vertical edges thereof are provided with the strap, 18, sliding in the bracket, 19, by means of which strap 18 the outer edge of the distributing plates may be secured by riveting or otherwise, 15 to the wall of the casing top or head in any desired position. More than one distributing plate, 16, may be hooked upon or secured to a single bar, 14, so that the number of distributing plates that may be inserted 20 in a casing top or head is much greater than the number of lead openings circumstances would require or the furnace supply.

With the above structure the relative amount of hot air distributed to any lead is 25 determined by the segment of the top allotted to its particular opening by the distributing plates. In actual practice it is easy to adjust the distributing plates with a little experimenting so that each lead receives its 30 proper proportion of hot air, and the little

hall bedroom way off in the end of the house receives heat as regularly and certainly as the living room which may be located directly over the furnace.

Having described my invention what I 35 claim as new and desire to secure by Letters Patent, is:—

A hot air distributor comprising a hot air casing, a heating element within said casing, the top of said casing being provided with 40 apertures for connection with hot air conduits, a reel located centrally with respect to the top of said casing, a series of concentrically and consecutively disposed bars in said reel, plates, means upon the ends of said 45 plates for engaging said vertical bars, and means for securing the outer edges of said plates to the outer walls of the top of said casing, said plates being adapted to divide only that space above the heating element 50 into variable segments of suitable proportion to the apertures opening into such respective segments.

In testimony whereof I affix my signature in the presence of two witnesses.

ALBERT G. SCHERER.
